JOHN S. BUCKMAN, OF FLUSHING, NEW YORK

COLLAPSIBLE TABLE

Application filed March 17, 1930. Serial No. 436,505.

Important objects of the present invention are, to provide an extremely cheap and simply constructed foldable table designed to be collapsed to a very compact form; to provide 5 a practical and satisfactory table of this sort made of pasteboard or similar sheet material; to provide such a table designed to fold into a flat sheet form; and to provide a cheap but satisfactory table intended particularly for use in public places for bridge 10 playing and the like, designed to be readily set up when required and to be readily collapsed to a compact form so that a large number of tables may be stored in a small 15 space when they are not needed.

In the drawings, Fig. 1 is a plan view of the table in collapsed form;

Fig. 2 a side edge view of the collapsed table;

Fig. 3 a bottom edge view of the collapsed table;

Fig. 4 a view similar to Fig. 3 showing the table partly unfolded;

Fig. 5 a bottom plan view of the table 25 further unfolded;

Fig. 6 a view of one side of the table;

Fig. 7 a view of another side of the table;

Fig. 8 a horizontal section taken on the line 8—8 of Fig. 6;

Fig. 9 a detail section on a larger scale, 30 taken on the line 9—9 of Fig. 7;

Fig. 10 an enlarged detail section taken on the line 10—10 of Fig. 8; and

Fig. 11 a perspective view of the set up 35 table.

The table is preferably constructed almost entirely from two flat sheets 1 and 2 of pasteboard or similar cheap sheet material which possesses sufficient stiffness but may be creased and folded. Sheets 1 and 2 are exact duplicates and are superposed in face to face contact with their contours in accurate register. Each sheet has a relatively rectangular lower portion 3 which is foldable 40 to form the supporting structure of the table, and a smaller rectangular upper portion 4 which is foldable to form the table top. Said upper portion is centered at the upper edge of the lower portion, and, coincident with 45 said edge both sheets are formed with slits

5 extending inwardly from their opposite side edges. Said slits are of equal length and between their inner ends both sheets are horizontally creased, as at 6 to form hinge connections between the upper and lower portions of the sheets.

The lower portion 3 of each sheet is vertically creased, as at 7 along parallel vertical lines extending downward from the ends of the horizontal crease 6. Below the latter 60 crease both sheets are formed with a slit extending horizontally between the creases, as at 8, curving outwardly and downwardly in opposite directions as at 9, beyond the creases 7, and then converging inwardly and 65 downwardly to said creases, as at 10. This slit partly encloses a central portion of each sheet and said central portion is creased as at 11 to fold along a horizontal line extending across it between the outermost points thereof. Extending obliquely inward from the 70 outwardly curved portions of said slit are short slits 12. The central portion interrupts the continuity of the vertical creases 7 which extend to the lower edges of the sheets.

Below the crease 11 and between the 75 creases 7 the sheets are secured together face to face in any suitable manner as by staples or rivets 13 which are disposed in rows extending along said creases. Between the 80 horizontal crease 6 and the portion 10 of the slit the sheets are similarly secured together in face to face contact by staples or rivets 13 disposed in rows extending along said crease and slit and between the creases 7. Said 85 riveted portions of the sheets, between the creases 7, form a double-ply central web 14 while the portions located without said web form two pairs of opposed side leaves 15 which are adapted to be spread apart to 90 operative positions. The central portions defined by the irregular slit and by the horizontal crease 11 form two opposed leaves 16 which are adapted to be spread apart to engage the leaves 15 and hold them in operative 95 position. The outwardly pointed riveted portions 17 beneath the ends of the crease 11 form a support to brace the leaves 15 at their hinged points.

The opposed upper portions 4 of the sheets 100

1 and 2 form leaves which are adapted to be folded outward in opposite directions at the creases 6 into a horizontal plane to form the table top. Each of said leaves is formed with fold creases 18 extending along the opposite side edges thereof and with a fold crease 19 extending along the upper edge of the leaf between the creases 14. Short slits 20 extend inwardly from the opposite side edges of the leaf to meet the crease 19. Along the slits 5 hinge strips of suitable flexible material 21 are pasted or otherwise secured to the leaves 4. These strips extend clear to the side edges of the leaves and the creases 18 extend across them also. The purpose of creases 18 and 19 is to define margins 22 and 23 which are downwardly foldable to finish the edges of the table top. Each leaf 4 is provided at its outer corners with snap fastening elements 24 and with companion snap fastening elements 25 disposed upon the side margins 22, directly below the short slits 20. Said companion elements are adapted to be lockingly engaged to hold said margins folded down and to hold the table top flat as will be described hereinafter.

In setting up the table the side leaves 15 are spread apart to divergent positions as shown in Fig. 5. Then, the central leaves 16 are separated and swung outward in opposite directions to lie in a horizontal plane. Said leaves then engage the side leaves 15 with the inner, cut out edges of the latter fitting in the short slits 12. The inner ends of slits 12 are then disposed in the sharp corners formed by the meeting portions 9 and 10 of the irregular central slit. Thereby the leaves 16 are held in horizontal operative position and serve to brace the leaves 15 and hold them in operative position. The curvature of the slit portions 9 serves to guide the leaves 16 into said holding engagement with leaves 15. Having thus prepared the supporting structure the leaves 4 are separated and are folded down flat upon said structure. The various parts of the latter are so proportioned and positioned with relation to the top-forming leaves 4 that when said leaves are folded down the outer ends of the leaves 15 are disposed in the corners defined by the margin creases 18 and 19 in plan, as shown in Fig. 5. Next, the margins 22 and 23 outside of the creases 18 and 19 respectively are folded down and the corner margin portions or tabs bearing the fastening elements 24 are folded laterally inward to lockingly engage said elements with the elements 25. Thereby the margins are held folded down. The margins 22 of the two leaves are joined by the hinge strips 21 and said strips are also folded down with the margins to form one continuous downturned margin at each side of the table top and serve to hold the table top flat. The downwardly turned and fastened margins stiffen the table

top and engage the supporting leaves 15 at the corners to brace said leaves and assist in holding them in place. In its set up condition the table structure is well braced throughout and is stiff and sturdy.

When the table is to be collapsed the fastening elements 24 and 25 are released and the leaves 16 are swung upward to free the leaves 15. The entire table structure may then be folded into the flat blank form shown in Fig. 1 with the leaves of each pair in face to face contact. In this flat, compact form large numbers of the tables may be stacked and stored in a limited space.

While I have shown a very satisfactory form of my invention I do not wish to be limited strictly to this disclosure but reserve the right, to make such changes as will lie within the scope of the claims.

What I claim is:

1. A collapsible table comprising a pair of similar superposed sheets of pasteboard or equivalent material having opposed table top leaf portions at one end foldable outward and downward away from each other to together form the table top, opposed portions along both longitudinal sides of the superposed sheets below said top leaf portions foldable laterally outward away from each other to form supports for the top leaf portions, and opposed intermediate portions foldable outward away from each other along lines extending transversely of the sheets to engage said top leaf supports and releasably hold them in supporting position, the sheets being secured together face to face between said leaf supporting portions below said top forming leaf portions.

2. A collapsible table comprising a pair of similar superposed sheets of pasteboard or equivalent sheet material having opposed top leaf forming portions foldable outward and downward away from each other to together form the table top, opposed leaf supporting side portions foldable laterally outward away from each other to form upstanding supports for the top leaf portions, and opposed bracing and locking portions foldable away from each other and interfitting with the leaf supporting side portions to releasably hold them in supporting position, the sheets being secured together face to face between said leaf supporting side portions.

3. A collapsible table comprising a pair of similar superposed sheets of pasteboard or equivalent sheet material having opposed top leaf forming portions foldable outward and downward away from each other to together form the table top, opposed leaf supporting side portions foldable laterally outward away from each other to form upstanding supports for the top leaf portions, and opposed bracing and locking portions foldable away from each other and interfitting with the leaf supporting side portions.

each other and interfittable with the leaf supporting side portions to releasably hold them in supporting position, the sheets being secured together face to face between said leaf 5 supporting side portions, and means to releasably hold the top leaves down upon their supporting portions.

4. A collapsible table comprising a pair of similar superposed and attached sheets of stiff 10 foldable material having opposed upper portions foldable outward and downward away from each other to form the table top, and opposed portions at each side of said attached sheets foldable laterally outward away from 15 each other to engage at their upper ends under the table top portions to support the table top portions in a horizontal plane.

5. A collapsible table comprising a pair of similar superposed sheets of stiff foldable 20 material having opposed upper portions forming leaves foldable outward and downward away from each other to form the table top, opposed side portions forming leaves foldable laterally outward away from each 25 other to form upstanding supports for the table top leaves, means to releasably hold said supporting leaves in supporting position, and means to releasably hold said top-forming leaves in operative position.

30 6. A collapsible table comprising a pair of similar superposed sheets of pasteboard or equivalent stiff foldable material both slit transversely from each longitudinal edge and creased between the ends of the slits to fold 35 along a horizontal intermediate line and both creased along a pair of spaced parallel vertical lines extending downwardly from the inner ends of said slits to the lower edges of the sheets, the sheets being secured together in 40 face to face contact between said vertical creases, the opposed sheet portions above the horizontal crease being foldable outwardly and downwardly away from each other to form the table top, and the opposed sheet portions located outside of said vertical creases being foldable outward away from each other into diverging positions to form supports for 45 the table top extending toward the four corners of the table top along their upper edges.

50 7. A collapsible table comprising a pair of similar superposed sheets of pasteboard or equivalent stiff foldable material both slit transversely from each longitudinal edge and creased between the ends of the slits to fold 55 along a horizontal intermediate line and both creased along a pair of spaced parallel vertical lines extending downwardly from the inner ends of said slits to the lower edges of the sheets, the sheets being secured together in face to face contact between said vertical creases, the opposed sheet portions above the horizontal crease being foldable outwardly and downwardly away from each other to form the table top, and the opposed sheet portions located outside of said vertical 60

creases being foldable outward away from each other into diverging positions to form supports for the table top extending toward the four corners of the table top along their upper edges, said sheets being slit and transversely creased to afford flaps terminating short of the sheet edges foldable outwardly away from each other, said flaps and the portions of the sheets located outside the vertical creases having portions interlockable to releasably hold the top supporting portions in 70 operative position.

8. A collapsible table comprising a pair of superposed sheets of material both creased to fold along a horizontal line to form similar 80 opposed leaves above said line foldable outward and downward away from each other to form the table top, said sheets being attached below said line and vertically creased to form foldable leaves below the table top to 85 support the top leaves, said top leaves having downwardly foldable marginal portions provided with snap fastening means to hold said marginal portions folded down.

9. A collapsible table comprising a pair of superposed sheets of material both creased to fold along a horizontal line to form similar 90 opposed leaves above said line foldable outward and downward away from each other to form the table top, said sheets being attached below said line and vertically creased to form foldable leaves below the table top to 95 support the top leaves, said top leaves having downwardly foldable marginal portions, and means for releasably connecting said 100 marginal portions to form a continuous tie extending around the table top to hold the top forming leaves against upward folding.

10. A collapsible table comprising a flat central web; a pair of opposed leaves hinged to the upper end of said web to fold downward and outward away from each other and form the table top; and two pairs of opposed leaves hinged to the opposite side edges of the web to fold laterally away from each other to 105 diverging positions to support the table top.

11. A collapsible table comprising a flat central web; a pair of opposed leaves hinged to the upper end of said web to fold downward and outward away from each other and form the table top; two pairs of opposed leaves hinged to the opposite side edges of the web to fold laterally away from each other to 115 diverging positions to support the table top; and a pair of leaves hinged to the web to fold outward to engage said supporting leaves and hold them in supporting position.

12. A collapsible table comprising a pair of superposed sheets of material both creased to fold along a horizontal line and along a 120 pair of spaced vertical lines extending downward from said horizontal line to the lower edges of the sheets, the sheets being secured together in face to face contact between said 130

creases thus forming opposed leaves above the horizontal crease foldable outward and downward away from each other to form the table top, and opposed leaves outwardly of the vertical creases foldable laterally outward away from each other to form supports for the table top, both sheets being formed with an intermediate slit defining opposed leaves foldable outward away from each other to engage and brace said supporting leaves.

13. A collapsible table comprising a flat central web; a leaf hinged to the upper end of said web to fold downward for forming the table top; and a pair of upright supporting leaves hinged to the opposite side edges of the web to fold laterally outward and extend across the under side of said top leaf to support it, said web and leaves being collapsible into a flat form.

14. A collapsible table comprising a sheet of stiff foldable material creased along parallel vertical lines to form laterally foldable supporting leaves outwardly of said creases, and medially slit and creased transversely to form a flap foldable outward to engage and releasably hold said side leaves in operative position; another sheet superposed upon said first sheet and secured to it face to face; and a leaf hinged to one of said sheets and foldable downward to rest upon the upper ends of said supporting leaves for forming the table top.

In testimony whereof I hereunto affix my
35 signature.

JOHN S. BUCKMAN.
